UNITED STATES PATENT OFFICE.

JOHN WREN, OF DEUNQUAT, OHIO.

FENCE-POST.

SPECIFICATION forming part of Letters Patent No. 391,395, dated October 16, 1888.

Application filed May 31, 1888. Serial No. 275,588. (No model.)

To all whom it may concern:

Be it known that I, JOHN WREN, a citizen of the United States, and a resident of Deunquat, in the county of Wyandot and State of Ohio, 5 have invented certain new and useful Improvements in Fence-Posts; and I do declare the following to be a full, clear, and exact description of the invention, such as will enable others skilled in the art to which it appertains to 10 make and use the same, reference being had to the accompanying drawings, and to letters or figures of reference marked thereon, which form a part of this specification.

Figure 1 of the drawings is a representation 15 of this invention and is a back view. Fig. 2 is a side view, partly in section. Fig. 3 is a cross-section.

The invention relates to improvements in fence-posts; and it consists in the construction 20 and novel combination of parts, as hereinafter set forth.

The object of the invention is to provide a metal fence-post which is seated in the ground, and from which the fence may be easily removed when desired. 25

Referring to the drawings, A designates the metal post, having its lower end firmly seated in the ground.

The post is preferably made of flat metal, 30 and has its edges B turned inwardly to form a dovetail flange, a.

The wooden post C, to which the fence-rails are attached, has the beveled edges b, adapted to

slide between the flanges a. The flanges a have the depressions c slightly above the surface of 35 the ground, forming shoulders or rests for the lower end of the post C, which prevent said post C from coming in contact with and absorbing dampness from the ground.

If desired, the post C may be secured in 40 the metal post A by means of nails or pins d, driven through openings e of the metal post into the wood of the post C.

I am aware that posts combining metal 45 and wood provided with dovetailed flanges have heretofore been patented, and such I do not claim, broadly. I am not aware, however, that the metal portion has been provided with the depressions in its flange for the purpose of holding the end of the wooden portion clear 50 of the ground.

Having described my invention, what I claim is—

The combination, with the wooden fence-post having beveled edges, of the metal post having its sides turned inwardly, forming the dovetail flanges a, adapted to engage the edges of the post C, and the depressions c in said flanges adapted to hold the bottom of the post C above 55 the ground, substantially as specified. 60

In testimony whereof I affix my signature in presence of two witnesses.

JOHN WREN.
